HOUSING FOR A PHONOGRAPH CARTRIDGE

Donald G. Haines, 226 Grace Ave., Elmhurst, Ill.

Filed Nov. 2, 1964, Ser. No. 82,414

Term of patent 14 years

(Cl. D26—14)

FIG. 1 is a front, top and right side perspective view of a housing for a phonograph cartridge, showing my new design;

FIG. 2 is a right side elevational view, the opposite side being substantially a mirror image thereof;

FIG. 3 is a top plan view;

FIG. 4 is a bottom plan view, to a reduced scale;

FIG. 5 is a front elevational view, to a reduced scale; and

FIG. 6 is a rear elevational view thereof.

I claim:

The ornamental design for a housing for a phonograph cartridge, as shown and described.
